UNITED STATES PATENT OFFICE.

CHARLES P. KNAPP, OF NEW YORK, N. Y., ASSIGNOR OF ONE-HALF TO WILLIAM H. MACK, OF JOHNSON CITY, NEW YORK.

DESIGN FOR A SMOKER'S STAND OR THE LIKE.

Application filed February 17, 1927. Serial No. 20,794. Term of patent 7 years.

To all whom it may concern:

Be it known that I, CHARLES P. KNAPP, a citizen of the United States, and a resident of the city of New York, borough of Manhattan, in the county and State of New York, have invented a new, original, and ornamental Design for Smokers' Stands or the like, of which the following is a specification, reference being had to the accompanying drawing, forming part thereof.

The figure is a perspective view of a smoker's stand, showing my new design.

I claim:

The ornamental design for a smoker's stand or the like, as shown.

CHARLES P. KNAPP.
